UNITED STATES PATENT OFFICE.

LESLIE R. McDONALD, OF MONTREAL, QUEBEC, CANADA.

AUTOMATIC REPEATING MECHANISM FOR PHONOGRAHS.

1,393,229.

Specification of Letters Patent. Patented Oct. 11, 1921.

Application filed March 24, 1920. Serial No. 368,264.

To all whom it may concern:

Be it known that I, LESLIE R. McDONALD, a citizen of the United States, residing at Montreal, Province of Quebec, Dominion of Canada, have invented certain new and useful Improvements in Automatic Repeating Mechanism for Phonographs, of which the following is a specification.

My invention relates to means whereby the reproducer or sound box, carried by the tone arm of a phonograph or similar sound reproducing device, and operating in conjunction with a disk record, after traveling, from its initial position, inwardly across the record, may be automatically lifted out of contact therewith and moved back to its starting point, so as to again travel over and interpret the record. And my improvements are directed particularly to means whereby this is accomplished in a positive and accurate manner, without undue shock or jar to the mechanism employed, and by means which can be readily attached to and disconnected from the phonograph mechanism; all as I will now more fully explain, referring in so doing to the accompanying drawings, in which Figure 1 is a plan view of the motor board, tone arm, sound box and turn table of a phonograph, with a disk record carried upon the turn table, and showing my repeater mechanism mounted thereupon; Fig. 2 is an elevation of the same on an enlarged scale, taken on a line looking in the direction of the arrow in Fig. 1 and at right angles to the axis of the radial arm, which is omitted for clearness, the left hand portion of the motor board, turn-table and disk being broken away, the repeater mechanism being shown in its initial position; Fig. 3 is a similar view, showing the repeater mechanism in its reproducer returning position; Fig. 4 is a vertical sectional view, on a still further enlarged scale, of the base, worm piston and dash-pot cylinder; Fig. 5 is a side view and Fig. 6 a front view of the adjustable support for the radial return rod; Fig. 7 is a perspective view of the dash-pot retaining ring; Fig. 8 is a detail of the top of the worm piston; Fig. 9 is a plan view of the worm engaging member carried by the radial return rod; Fig. 10 is a plan view of a section of the radial return rod and of the inner stop carried thereby; and Fig. 11 is a view of the same, looking to the left on line 11-11 of Fig. 10.

Similar parts are designated by corresponding reference numerals in all the figures.

The motor board 1, turn table 2, disk 3, tone arm 4, and sound box 5 are those of a standard phonograph or similar sound reproducing machine. The spindle 6 on the upper end of the shaft, shown in broken lines in Fig. 3, projects through the center of the record disk 3, in the usual manner. And over this spindle, and resting on the record, I place a base 7, carrying a worm piston 8, the lower end of which is provided with a spindle gripping device, which I have illustrated as consisting of a sleeve 9, screwed into the lower part of the worm piston, and split so as to permit its parts to yieldably embrace and grip the spindle. The thread 10 in the worm piston is preferably an acute trapezoidal thread. And, in practice, I have found that a face angle of about 80 degrees, and a pitch of from .15" to .20" gives satisfactory results. The upper end of the thread gradually merges into the surface of the worm piston, as shown at 10^a in Fig. 8.

The upper end of the worm cylinder is slightly enlarged, as at 11, and, preferably, terminates in an under-cut boss 12, around which is slipped a thin flexible washer 13.

A retaining ring 14 is adapted to slide upon the body of the worm cylinder, but is prevented by the enlargement 11 from escaping over its top.

A dash-pot cylinder 15, slides over the worm piston 8, and is provided at its lower end with an annular enlargement 16 into which the retaining ring 14 fits snugly; so that, when the ring and the cylinder have been assembled around the worm piston, the dash-pot cylinder may not be drawn entirely up off the worm cylinder without the use of force sufficient to separate it from the retaining ring 14.

The dash-pot cylinder 15 is provided near its bottom with a recess or slot 17 on each side, and with an opening 18 between the slots 17, which slots slidably receive the arms 19, 20 of the forked member 19, which is also provided with a downwardly bent prong 20 adapted to enter through the opening 17, the forked member 19 being arranged to have a slight sliding movement in the slots 17, but to be kept, by the deflection of the points of its arms 18, 19, or by other suitable means, from slipping out of the slots; this

sliding movement being sufficient to allow the prong 20 to be pushed into or withdrawn from the groove 10 in the worm cylinder.

The forked member 19 is rigidly secured 5 to one end of a rod 21, the main portion of which is bent upon a true curve coinciding with the sweep of the sound box when moving with the radial tone arm; the outer end of the rod 21 sliding through a slot 22 in a 10 guide 23 which carries a slideable support 24, by means of which the elevation of the outer end of the rod 21 may be regulated. The guide 23 is secured to the motor board, as by a screw 25, or other suitable means.

15 This rod 21 carries an outer, adjustable stop 26, which I have shown as consisting of a piece of spring metal having perforated and diverging arms 27, 28, the arm 28 being provided with a flange 29 adjusted to bear 20 against and slidably grip the rod 21, which is milled flat on its under side to prevent the stop from turning on it. By pinching the arms of the stop together its grip on the rod will be relaxed, and it can be slid back 25 and forth as desired.

The inner stop 30 embodies means whereby it is slidably and yieldably mounted upon the rod 21. These means are shown as consisting of two arms 31 and 32, carrying 30 flanges 33 and 34 pierced to receive the rod 21, the opening in the flange 34 being elongated so as to allow the flange to play slightly to and fro on the rod. Another arm 35 presses against the flattened under- 35 side of the rod, so as to resist the turning of the stop around the rod.

A coiled spring 36 fits snugly around the rod, its end 37 being hooked over the flange 34 so as to normally draw 40 that end of the flange in toward the rod as far as its elongated opening will permit; thus throwing the free end of the stop 30 slightly forward and holding it yieldably in that position. The end of the stop is 45 preferably covered with a sound deadening and shock absorbing element, as 38, which may be of rubber or similar material.

The repeater mechanism may be assembled upon a phonograph machine by putting 50 a disk record in place and then pressing the base 7 with the dash-pot cylinder and rod 21 attached to it down over the spindle 0 of the shaft 6, which it will grasp so as to be rotated therewith.

55 The guide 23 having been secured to the motor board, the outer end of the rod will slide therethrough, and may be adjusted to a suitable height by means of the sliding support 24.

60 Care should be taken in adjusting the rod 21 to see that the curve of the rod coincides with the arc traversed by the sound box, and also that in its initial position the rod lies substantially parallel with the face of 65 the record.

To adjust the mechanism to the particular record to be repeated, place the needle in the reproducer and tip down the reproducer with the needle in the outside groove, then gently press the radial arm outward so as 70 to take up the slack or end play of the rod, and at the same time gently slide the outside stop inward until it just comes in contact with the reproducer.

Next, lift up the reproducer and move it 75 inward, setting the needle in the inside or finishing groove of the record; after which gently press outward the inside actuating stop until the same comes in contact with the needle. Owing to the fact that most 80 records are more or less eccentric, it is better to make this adjustment with the needle set five or six grooves from the last or inside groove.

Then shift the reproducer back to the 85 starting point of the record and start the machine.

The reproducer will then be carried along, 90 slightly above the radial rod 21, until it reaches the stop 38, against which it will be pressed, causing the stop to yield slightly against the tension of the spring 36 and then to move on before the sound box, carrying with it the radial rod 21, causing the prong 20 on the member 19 to come in contact with the worm piston 8. At this point the spring 36 performs an important function. For the reproducer or sound-box, moving slowly inward, because of eccentricities on the record, seldom proceeds at a 95 uniform rate. And if it was pressed positively and unyieldably against the surface of the worm piston and its progress arrested thereby, the needle would be forced to ride out of its groove in the record as it 100 continued to revolve. However, the flexibility of the stop 30 allows the needle to push the stop ahead of it, until the revolution of the worm piston brings the worm groove around to the prong 20, which will 105 then enter the groove, and be carried upward, as the worm piston continues to revolve, lifting with it the dash pot cylinder and the end of the rod 21.

When the rod has been raised a little distance it will pick up the sound box and will 115 carry it upward until the inclination of the rod is such that the weight of the sound box will cause it to slide down along the rod, and come against the outer stop 26, the impact 120 of the sound box against the stop 26 causing the rod 21 to slide outward, withdrawing the prong 20 from the worm groove 10 and allowing the dash-pot cylinder to slide gently down the worm piston, as the air 125 gradually escapes from within the cylinder, until the rod 21 has reached its initial position, when the needle will have again entered the groove in the record, and the repetition of the record will again take place. 130

If the prong 20 is not withdrawn from the groove by the sound box striking the stop 26, it will be automatically disengaged therefrom when it reaches the end 5 of the groove, the merging of the groove into the surface of the cylinder having the effect of a cam to disengage the holder 20 from the worm 10, the holder riding out onto the surface of the worm piston. For 10 the weight of the rod 21, and of the sound box resting on the rod, will cause it immediately to slide outward to the limit of movement permitted by the arms 18, 18 of the element 19, preventing the hook 20 from reentering 15 the groove 10 as the arm falls to a horizontal position.

By means of my improvements I secure a simple and efficient device, which may be quickly and conveniently attached to and 20 removed from a phonograph, and which will raise the reproducer away from the record disk and return it to its initial position and place it again in the groove of the record, without undue shock or noise 25 or jar to any part of the apparatus.

It is obvious that details of construction may be varied, by the use of mechanical equivalents, or the like, without departing from the spirit of my invention as claimed.

30 Having thus described my invention, what I claim and desire to secure by Letters Patent of the United States is:—

1. The combination, in a sound reproducing instrument embodying a rotatable record support and a movable tone-arm provided with a sound box and a record following needle, of automatic means for raising the sound box from the record to permit the sound box to swing outward, and pneumatically checked means, centrally disposed relative to the rotatable record support, for retarding the return descent of such raising means.

2. The combination, in a sound reproducing instrument embodying a rotatable record support and a movable tone-arm provided with a sound box and a record following needle, of automatic means for raising the sound box from the record to permit the sound box to swing outward, and pneumatically checked means, centrally disposed relative to the rotatable record support, and embodying a dash-pot cylinder in combination with the raising means, for retarding the return descent of such raising means.

3. The combination, in a sound reproducing instrument embodying a rotatable record support and a movable tone-arm provided with a sound box and a record following needle, of automatic means, embodying a sound-box supporting-rod for raising the sound box from the record to permit the sound box to swing outward, and pneumatically checked means, centrally disposed

relative to the rotatable record support and 65 embodying a rotatable worm piston and a dash-pot cylinder mounted thereupon, for retarding the return descent of such raising means.

4. The combination, in a sound reproducing instrument embodying a rotatable record support and a movable tone-arm provided with a sound box and a record following needle, of automatic means for raising the sound box from the record to permit the 70 sound box to swing outward, embodying a rotatable worm piston, a dash-pot cylinder mounted thereupon, and a longitudinally movable sound-box supporting-rod adapted to be raised by said worm piston and to be 75 delayed in its return descent by such dash-pot cylinder.

5. The combination, in a sound reproducing instrument embodying a rotatable record support and a movable tone-arm provided 80 with a sound box and a record following needle, of automatic means for raising the sound box from the record to permit the sound box to swing outward, embodying a rotatable worm piston, a dash-pot cylinder 85 mounted thereupon, and a longitudinally movable sound-box supporting-rod, provided with means for detachably engaging the worm of said piston, adapted to be raised at one end by said worm piston and 90 to be delayed in its return descent by such dash-pot cylinder.

6. The combination, in a sound reproducing instrument embodying a rotatable record support and a movable tone-arm provided 95 with a sound box and a record following needle, of a longitudinally movable, sound-box supporting-rod and a vertically adjustable support for the outer end of said rod, adapted to permit longitudinal movement of 100 the rod in relation thereto.

7. The combination, in a sound reproducing instrument embodying a rotatable record support, movable tone-arm, sound box and needle, of a slidable and inclinable tone-arm 110 supporting-rod provided with an inside stop adapted to intercept the movement of the sound box and to thereby slide the supporting-rod bodily in one direction, and also provided with an outside tone-arm stop, adapted to intercept the movement of the sound box and to thereby slide the supporting-rod 115 bodily in the other direction.

8. The combination, in a sound reproducing instrument embodying a rotatable record support, movable tone-arm, sound box and needle, of a slideable and inclinable tone-arm supporting-rod provided with a yieldable inside stop adapted to intercept the movement of the tone-arm and to thereby slide the supporting-rod bodily in one direction, and also provided with a yieldable outside stop, adapted to intercept the move- 120 125

ment of the sound box and to thereby slide the supporting-rod bodily in the other direction.

9. The combination, in a sound reproducing instrument embodying a rotatable record support and a movable tone-arm provided with a sound box and a record following needle, of automatic means embodying a rotatable piston, provided with a worm having a downwardly and inwardly inclined upper face, sound-box supporting-rod guiding means, a sound-box supporting-rod provided with holding means for detachably engaging the worm of said piston, means actuated by the movement of the sound box for causing such engagement, and means similarly actuated for terminating the engagement.

10. The combination, in a sound reproducing instrument embodying a rotatable record support and a movable tone-arm provided with a sound box and a record following needle, of automatic means embodying a rotatable piston, provided with a worm having a downwardly and inwardly inclined upper face, sound-box supporting-rod guiding means, a sound-box supporting-rod provided with holding means, consisting of a deflected element, for detachably engaging the worm of said piston, means actuated by the movement of the sound box for causing such engagement, and means similarly actuated for terminating the engagement.

11. The combination, in a sound reproducing instrument embodying a rotatable record support and a movable tone-arm provided with a sound box and a record following needle, of automatic means embodying a rotatable piston, provided with a worm, and a dash-pot cylinder provided with an opening therethrough and with rod guiding means and mounted on the piston, a sound-box supporting-rod provided with elements coöperating with said rod guiding means and with holding means, consisting of a deflected element, passing through said opening in the dash-pot cylinder, for detachably engaging the worm of said piston, means actuated by the movement of the sound box for causing such engagement, and

means similarly actuated for terminating the engagement.

12. The combination, in a sound reproducing instrument embodying a rotatable record support and a movable tone-arm provided with a sound box and a record following needle, of automatic means embodying a rotatable piston, provided with a worm having an inwardly and downwardly disposed depression in its upper face, sound-box supporting-rod guiding means detachably mounted thereupon, a sound-box supporting-rod provided with holding means for detachably engaging the worm of said piston, means actuated by the movement of the sound box for causing such engagement, and means similarly actuated for terminating the engagement.

13. The combination, in a sound reproducing instrument embodying a rotatable record support and a movable tone-arm provided with a sound box and a record following needle, of automatic means embodying a rotatable piston, provided with a worm, supporting-rod guiding means, embodying a dash-pot cylinder, associated with the piston, a sound-box supporting-rod, in slidable relation to the dash-pot cylinder, provided with holding means for detachably engaging the worm of said piston, means actuated by the movement of the sound box for causing such engagement, and a plurality of means for terminating such engagement.

14. The combination, in a sound reproducing instrument embodying a rotatable record support and a movable tone-arm provided with a sound box and a record following needle, of automatic means embodying a rotatable piston, provided with a worm having a raised marginal element upon its upper edge, supporting-rod guiding means associated with the piston, a sound-box supporting-rod provided with holding means for detachably engaging the worm of said piston, means actuated by the movement of the sound box for causing such engagement, and a plurality of means for terminating such engagement.

LESLIE R. McDONALD.
